FOREIGN PATENT DOCUMENTS

WO 2012135069 10/2012

Primary Examiner — Katrina A Betton(74) *Attorney, Agent, or Firm* — Sierra IP Law, PC;
William K. Nelson(57) **CLAIM**

I claim the ornamental design for a cargo compartment net, as shown and described.

DESCRIPTION

FIG. 1 is a perspective view of a cargo compartment net showing my new design;

FIG. 2 is a top view of the top of the cargo compartment net of FIG. 1;

FIG. 3 is a bottom view of the bottom of the cargo compartment net of FIG. 1;

FIG. 4 is first side view of the cargo compartment net of FIG. 1;

FIG. 5 is second side plan view of the cargo compartment net of FIG. 1;

FIG. 6 is a third side view of the cargo compartment net of FIG. 1;

FIG. 7 is a fourth side view of the cargo compartment net of FIG. 1;

FIG. 8 is a view showing engagement of brackets and a suspension pole of the cargo compartment net of FIG. 1; FIG. 9 is a view showing engagement of the suspension pole with loops of the cargo compartment net of FIG. 1; and, FIG. 10 is an environmental view of the cargo compartment net of FIG. 1 installed in a cargo compartment.

The broken lines shown in the figures are for the purpose of illustrating portions of the cargo compartment net that form no part of the claimed design.

1 Claim, 10 Drawing Sheets(56)
